UNITED STATES PATENT OFFICE

137,632

DESIGN FOR A HOUSING FOR A COMBINED MOTOR AND PUMP

Don Charles Asbury, Glendale, Calif., assignor to
Adel Precision Products Corp., a corporation of
California

Application February 4, 1944, Serial No. 112,444
Term of patent 14 years

(Cl. D65—1)

To all whom it may concern:

Be it known that I, Don Charles Asbury, a citizen of the United States and residing at Glendale, in the county of Los Angeles, State of California, have invented a new, original, and ornamental Design for a Housing for a Combined Motor and Pump, of which the following is a specification, reference being had to the accompanying drawing, forming part thereof, in which:

Fig. 1 is a side elevation of a housing for a com-

bined motor and pump showing my new design;

Fig. 2 is a top plan view of the housing;

Fig. 3 is an elevational view of one end of the housing hereof;

Fig. 4 is an elevational view of the other end of the housing hereof.

I claim:

The ornamental design for a housing for a combined motor and pump, as shown.

DON CHARLES ASBURY.
